UNITED STATES PATENT OFFICE

91,793

DESIGN FOR AN AUTOMOBILE SIGNAL LIGHT CASING

Harold O. Smith, Indianapolis, Ind.

Application June 30, 1933, Serial No. 48,609

Term of patent 14 years

To all whom it may concern:

Be it known that I, HAROLD O. SMITH, a citizen of the United States of America, residing at Indianapolis, county of Marion, State of Indiana, have invented a new, original, and ornamental Design for Automobile Signal Light Casing, of which the following is a specification, reference being had to the accompanying drawing, forming part thereof.

In the drawing:

Figure 1 is a front elevation of the signal light casing.

Figure 2 is a side elevation of the same.

The drawing shows a casing for an automobile signal light the dominant feature of which is the front indicated by reference character 1. This front consists of a front plate 2 of spider-like form having horizontally disposed pointer slots 3 in the form of arrow heads with the points

near the center and the flaring rear ends of the arrow heads turned outwardly, and top and bottom light openings 4 and 5 above and below the pointers. In addition to the front plate 2, the front 1 comprises an edge flange 6 which engages the front edge portion of the casing 7. The pointer slots 3 and the light openings 4 and 5 are closed or covered by transparent sheet material 8 which would ordinarily be red or other suitable colored glass in accordance with the regular practice in the construction of automobile stop, tail and signal light casings.

I claim:

The ornamental design for an automobile signal light casing as shown and described.

Signed by me at Baltimore, Maryland, this 27th day of June, 1933.

HAROLD O. SMITH.
